VARIABLE CAPACITY MEASURING CUP

Wendell W. Jennings, San Francisco, Calif.

Application September 7, 1948, Serial No. 48,033

6 Claims. (Cl. 73—429)

1

This invention provides an improved variable capacity measuring cup for culinary use; such cup being a modification of the cup shown in pending application, Serial No. 716,541, filed December 16, 1946, now Patent Number 2,478,272.

One advantage of the cup, as modified, resides in a novel and improved movable bottom assembly, the latter being operative to work in close wiping relation to the cylindrical body of the cup, and to prevent leakage between said bottom assembly and cylindrical body.

Another advantageous feature of the present embodiment of the cup is a novel and improved indexing device between the movable, cup bottom actuating lever and the handle of the cup; such indexing device being readily and conveniently manipulated, by the thumb of the hand which holds the cup, to set the latter to a selected capacity.

A further advantage of the present embodiment of the cup is its structural design, which permits of economy and ease of manufacture and assembly, in mass production.

A further object of the invention is to provide a practical and convenient measuring cup, and one which will be exceedingly effective for the purpose for which it is designed.

These objects are accomplished by means of such structure and relative arrangement of parts, as will fully appear by a perusal of the following specification and claims.

In the drawings:

Fig. 1 is a side elevation of the measuring cup.

Fig. 2 is an elevation, mainly in section, of the same.

Fig. 3 is a plan view of the cup with the flexible sealing disc partly broken away.

Referring now more particularly to the characters of reference on the drawings, the improved measuring cup comprises a cylindrical body 1, initially open from end to end thereof, and including beads 2 and 3 at opposite ends.

A circular, vertically movable bottom or plunger 4 is disposed in the body 1, with a relatively close sliding fit; such bottom 4 including a depending, annular guide skirt 5 which assures of easy sliding of said bottom 4 in the body 1.

The top of the bottom 4 is fitted with a flat but flexible sealing disc 6, preferably of an elastometric composition, such as "Vinylite," or the like; the disc including an annular wiping lip 7 at its periphery running in close wiping contact with the inner wall of the body 1 of the cup.

A locating boss 8, of rectangular shape, projects downwardly from the center of the disc 6, and engages in a matching slot 9 in the bottom 4. Additionally, a circumferential row of friction

2

buttons 10 is formed integral with the disc 6, projecting downwardly therefrom, in holding relation, through holes 11 in the bottom 4.

The above described flexible sealing disc 6 assures against leakage when the measuring cup is used with liquids, and further wipes the inner wall of the body clean.

The body 1 is formed, on the outside, with a plurality of vertically spaced ribs 12, of full circumferential extent, disposed in a vertical row; such ribs being sealed, as at 13, to indicate cup measurements above the bottom 4 when the latter is in its normal and lowermost position. These ribs also add strength to the cup, which may be 15 quite thin.

On one side thereof the body 1 is fitted with an outwardly projecting handle 14 of generally C-shape, and an actuating lever 15, preferably of metal, and generally in the form of a bellcrank, 20 is pivoted at the elbow, as at 16, to the lower portion of the handle 14 exteriorly of said body 1.

The lower leg 17 of lever 15 projects into the body 1, below the bottom 4, through an opening 18. The lower leg 17 is curved, at its free end 25 portion, and bears against the bottom 4, generally centrally thereof. Also, said curved inner end portion of the lower leg 17 passes through an opening 19 formed through the central part of the cross webs 20, which depend from the bottom 4. Said inner end portion of the lower leg 17 thus bears, at its upper edge, against the bottom 4 in lifting relation thereto, and bears, at its lower edge, on a fulcrum 21 in lowering relation to said bottom 4.

35 The other and upstanding leg 22 of the actuating lever 15 is formed, adjacent its upper end, with a generally C-shaped, laterally inwardly opening portion 23; the top of which portion provides a spring finger 24 which projects directly toward, and terminates substantially in engagement with, the side of the handle 14 at the top thereof. At the end adjacent the side of the handle 14, the spring finger 24 includes, in rigid relation therewith, a catch 25, and said 40 side of the handle 14 is formed with an arcuate groove 26. A plurality of notches 27 extend upwardly from said groove in spaced relation therewith; such notches being scaled in cup capacity, as shown.

50 The catch 25 projects into the groove 26, and the spring finger 24 urges said catch in a direction to frictionally engage the same in any selected one of the notches 27. The spring finger 24 includes an upwardly projecting thumb flange 28, by means of which the thumb of the hand which grasps the handle 14 may be employed 55 to swing the lever 15 to a selected position of

3

adjustment, while holding the spring finger sufficiently depressed that the catch 25 runs in the groove 26. When the thumb flange 28 is released, the spring finger 24 urges the catch 25 into a notch corresponding to a selected capacity.

For measuring liquids, the bottom 4 remains in its lowermost position, with catch 25 in notch 27 identified as "1 cup"; the liquid level then being read on the scale ribs 12.

For measuring solids, or semi-solids, the bottom is first manually adjusted to a selected capacity, and then the material to be measured is placed in the cup to the level of the top thereof. This material may then be ejected from the cup by swinging the leg 22 of lever 15 outwardly until disc 6 is flush with the top of the cup, as in dotted lines in Fig. 2, and at which time the material need not be dug out of the cup, and either slides from the disc or may be cleanly cut off the same. To facilitate ejection of such material from the cup, the latter may be heated, in warm water, before use; this causing the outer surface of the material in the cup to melt sufficiently to create a light film between the material and the inner wall of body 1.

At its outer end the groove 26 includes an inwardly offset, longitudinally extending end portion 29 which forms a stop shoulder 30. When the spring finger 24 is depressed to release catch 25, and the leg 22 of actuating lever 15 is swung outwardly in a direction until said catch 25 strikes the stop shoulder 30, the disc 6 is then flush with the top of the body 1, for the purpose above described.

Upon additional depression of the spring finger 24, to free catch 25 from shoulder 30, and further outward swinging of the leg 22 of actuating lever 15 until said catch 25 is fully advanced in the longitudinal end portion 29 of groove 26, the bottom 4 is thrust out of the top of the cup sufficient to permit of its easy removal; the inner end of the lower leg 17 then being in a position to escape the opening 19. In this manner the bottom 4 can be readily removed from the body 1 of the cup for cleaning, and then can be easily replaced. This arrangement also facilitates initial assembly.

The above described measuring cup provides a practical and convenient article for measuring, during culinary operations, of ingredients to relatively exact proportions.

The convenience of the cup is enhanced by the fact that it works easily, smoothly, and is capable of quick manual adjustment from one capacity to another, as desired.

From the foregoing description it will be readily seen that there has been produced such an article of manufacture as substantially fulfills the objects of the invention, as set forth herein.

While this specification sets forth in detail the present and preferred construction of the article of manufacture still in practice such deviations from such detail may be resorted to as do not form a departure from the spirit of the invention, as defined by the appended claims.

Having thus described the invention, the following is claimed as new and useful, and upon which Letters Patent are desired:

1. A measuring cup comprising a cylindrical body having a vertically movable bottom slidably mounted therein, a laterally projecting handle on the body, a manually actuated lever pivoted on and operative from the handle to adjust the bottom in the body, said lever including one leg projecting into the body and engaging the mov-

4

able bottom, said lever also including a second leg upstanding alongside the handle, the adjacent side of the handle having an arcuate groove therein, and a catch on the upstanding leg projecting into the groove; there being notches along said groove corresponding to selected positions of adjustment of the bottom, and means on the upstanding leg operative to yieldably seat the catch in said notches.

2. A measuring cup comprising a cylindrical body having a vertically movable bottom slidably mounted therein, a laterally projecting handle on the body, a manually actuated lever pivoted on and operative from the handle to adjust the bottom in the body, said lever including one leg projecting into the body and engaging the movable bottom, said lever also including a second leg upstanding alongside the handle, the side of the handle adjacent said upstanding leg having an arcuate groove therein, the upstanding leg having a generally C-shaped, laterally inwardly opening portion formed on the upper end thereof, said C-shaped portion forming a spring finger at the top of the leg projecting toward said groove, and a catch projecting from the finger into the groove; there being notches along the groove corresponding to selected positions of adjustment of the bottom, and said finger yieldably urging the catch in the direction of, and for engagement in, any selected one of said notches.

3. A measuring cup, as in claim 2, including a thumb engaging element upstanding from the spring finger.

4. A measuring cup comprising a cylindrical body having a vertically movable bottom slidably mounted therein, a laterally projecting handle on the body, a manually actuated lever pivoted on and operative from the handle to adjust the bottom in the body, said lever including one leg projecting into the body and engaging the movable bottom, said lever also including a second leg upstanding alongside the handle, the handle including a notched, longitudinal groove therein on the side adjacent the upstanding leg, and a catch projecting from said leg into the groove for releasable engagement with any selected notch thereof.

5. A measuring cup, as in claim 4, in which the manually actuated lever is arranged to thrust the bottom out of the top of the cup when the leg is swung to a position with the catch at one end of the groove; the bottom then being separable from said lever.

6. A measuring cup, as in claim 5, in which said one end of the groove is in a laterally offset, longitudinal portion of the groove, forming a shoulder against which the catch normally engages; the catch being manually depressible for entry into said portion of the groove to engage said end.
